(57) **CLAIM**

The ornamental design for a dental scalar, as shown and described.

DESCRIPTION

FIG. 1 is an isometric view of a dental scalar;
FIG. 2 is a front view of the dental scalar of FIG. 1;
FIG. 3 is a rear view of the dental scalar of FIG. 1;
FIG. 4 is a first side view of the dental scalar of FIG. 1;
FIG. 5 is a second side view of the dental scalar of FIG. 1;
FIG. 6 is a top view of the dental scalar of FIG. 1; and,
FIG. 7 is a bottom view of the dental scalar of FIG. 1.
Any other surface(s) or portion(s) of the dental scalar not
shown in the figures or otherwise described in the specifi-
cation form(s) no part of the claimed design.
